MEANS FOR PRODUCING MECHANICAL VIBRATIONS

Edwin E. Turner, Jr., West Roxbury, Mass., assignor to Submarine Signal Company, Boston, Mass., a corporation of Maine

Application July 21, 1936, Serial No. 91,797

6 Claims. (Cl. 21—61)

The present invention relates to an apparatus for producing vibratory energy and more particularly to the vibration of small volumes of liquid either under continuous flow or in enclosed volumes.

The apparatus of the present invention is preferably applied to vibrations in the upper part of the sonic range and in supersonic frequencies, and in particular for pathological work such as 10 treatment of liquids containing bacteria or other micro-organisms for various purposes.

One of the chief purposes of the present application is to provide vibrations of relatively large amplitudes at high frequencies and to 15 maintain the structure of such low weight and proportions that it may be used as a laboratory apparatus.

Another purpose of the present invention is to completely separate the element containing the 20 liquid to be vibrated from the electrical system and to so support the vibratory source that the mechanical system will always be free to vibrate.

Another feature of the present invention is a 25 system whereby the apparatus may be water-cooled and thus enable the liquid to be treated at the proper temperature at which the experimental work is to be performed.

The present invention will be more fully described in connection with the drawing which shows a vertical cross section through the center of the apparatus.

In the figure, 1 represents a base which is provided with a central opening 10 through 30 which the water-cooling system is inserted. Mounted on the base 1 is a shell 4 having a circular opening 11 at the top symmetrically placed with respect to the opening 10 in the base 1. The shell 4 may be cylindrical in shape with a dome-shaped space within, in which the coil 12 is 35 placed. It will also be noted that a cylinder 2 may project inwardly from the center of the base 1 surrounding the opening 10 and symmetrical with the opening 11 in the cylindrical shell 4. On the upper outside surface within a 40 grooved portion of the cylinder 2 there may be wound a coil 3 having conducting elements 13 leading out of the bottom of the device. The cylindrical shell 4, the base 1 and the element 2 45 form a magnetic path for the flux of the coil 12 and provide a magnetic air gap in a space 14 between the hole at the top of the cylinder 4 and the top of the collar or cylinder 2. The direct 50 current flux in this air gap may be varied by means of the current impressed upon the alter-

nating current coil 3. Within the air gap 14 there is placed a hollow tube 15 which may be capped over at the top as indicated at 16 and provided with a centrally located flange 17 which terminates in a cylindrical wall or shell 18 having an external flange 19.

The lower end 20 of the tube 15 may be made of some conductive material or plated with some such conductive material as, for instance, silver. The tube itself is preferably made of some high 10 sound conductive material in which the mechanical and acoustical losses are a minimum. A very suitable material for this purpose is beryllium copper. The tube 15 is supported by the external shell 7 which is fastened in the flange 15 21 by means of the bolts 22 to the base 1. This shell 7 has an inwardly projecting flange 8 upon which the flange 17 rests. The top flange 19 is surrounded with a rubber washer 23 U-shaped in section as shown surrounding the flange 19. 20

The threaded ring 24 presses against the washer 23 and forces the flange 17 firmly down against the flange 8, at the same time providing a watertight seal at the top around the flange 19. A second cover 25 may be provided over the 25 ring 24 and this clamped in place by means of the ring 26. The cavity 27 external of the upper part of the tube and within the shell 18 forms the container for the liquid which might be supplied and withdrawn by means of the tubes 30 28 and 29. Since the flange 17 is at the central portion of the tube it is also at a nodal point 35 of vibration and will therefore not interfere with the longitudinal vibrations of the tube. It will also be evident to those skilled in the art that 35 the end 20 of the tube 15 is in the air gap of a direct current electromagnet formed by the core 2 and the shell 4 and excited by the direct current magnet coil 12. The alternating current which passes through the coil 13 serves to 40 increase and decrease the strength of the magnetic field in the air gap, thereby inducing currents to flow in the end 20 of the tube 15 which, in turn, react upon the flux in the air gap to bring about an up and down movement of the 45 end 20 in the air gap. This motion sets up a longitudinal vibration in the tube 15 resulting in a large amplitude of vibration at the upper end 50 of the tube.

A means is provided for cooling the internal 50 side of the tube 15 in the upper portion where the liquid comes in contact with the tube. Within the opening 10 and the cylinder 2 there is provided an internal pipe 30 extending upward near the top 16 of the tube. The pipe 30 may be pro- 55

vided at the end with a spray nozzle 31 for spraying the cooling medium on the inside wall of the capped portion of the tube. The tube 30 is within a second tube 32 which may serve as an outlet for the liquid within the top part of the tube. A collar 33 is provided welded to the tube 32 at the top edge. This collar is slightly smaller than the internal diameter of the tube 15. Just below the collar 33 is a rubber collar 34 which is pressed outward by means of the collar 35 threaded to the external tube 32. In this way the cooling liquid is prevented from reaching the bottom of the tube where the electrical generating system is positioned. The rubber ring 34 which may, of course, be of any other suitable material is pressed against the tube 15.

Having now described my invention, I claim:

1. A device for applying vibrations to a liquid comprising a container having a tube projecting from the central portion of the base thereof, said base forming a web at the nodal point of the tube, said tube being capped at the end within the container, means supporting said container comprising a cylinder having an inwardly projecting flange upon which said container rests, said container at its top edge having an outwardly projecting flange and means applied above said flange for clamping said container within said cylinder and means for applying vibrations at the other end of said tube to vibrate the same longitudinally.

2. Means for supplying vibrational energy to a liquid mass comprising a container having a tube projecting from the base thereof, said base forming a web support at the nodal point of the tube, said tube being capped at its end within the container, an element supporting said container comprising a casing having an inwardly projecting flange upon which the container is adapted to be rested, means positioned at the top edge of said container and attached to said casing for firmly securing said container in said casing and electrical means applied at the base of the casing and associated with the other end of the tube for producing longitudinal vibrations of the tube.

3. Means for applying vibrational energy to a liquid medium comprising a container having a tube projecting from the base thereof, said base forming a rigid supporting nodal web for the support of said tube, said tube projecting inwardly into said container and being capped at said end, said other end of the tube being open and electri-

cal means applied at said open end for vibrating the tube, means supporting said container at said nodal web and means positioned within said tube for cooling the upper portion thereof within said container, said means being made watertight 5 within the tube at the point of said nodal support.

4. Means for producing vibrational energy comprising a metallic container having a central axis of symmetry with a centrally located tube 10 projecting upwards within said container and capped at the upwardly projecting end, rigid means joining said tube at its nodal point externally below the capped end to said container, means for making the interior section of said 15 tube at said joining means watertight comprising gasket means and means pressing said gasket means outwardly against the inner sides of the walls of said tube, means for circulating cooling water therein, and means forming a magnetic 20 airgap around the lower end of the tube, said lower end being open and positioned in said airgap and adapted to be vibrated by the variation of the magnetic flux therein.

5. Apparatus for vibrating liquids comprising 25 a supporting vertical casing having an interior projecting flange projecting from the wall of said casing forming a shelf, a container adapted to fit within said casing, said container having centrally and symmetrically located a vertically top 30 capped tube having an externally extending rigid nodal web comprising a shoulder adapted to rest on said shelf and means positioned at the bottom end of the tube for vibrating the same.

6. Means for producing vibrational energy 35 comprising a metallic container having a central vertical axis of symmetry with a centrally located tube projecting upwards within the container and capped at the upwardly projecting end, rigid means joining said tube at its nodal point externally below the capped end to said container, means for making the interior section of said 40 tube at said joining means watertight, means for circulating cooling water therein, and means forming a magnetic airgap around the lower end 45 of the tube, said airgap having the same shape as the lower end of the tube and said tube being aligned vertically therein and means positioned within said airgap for varying the magnetic flux therethrough whereby said tube will be vibrated 50 at its end.
